DESIGN FOR A PHONOGRAPH PICK-UP

Arthur C. Ansley, New York, N. Y.

Application February 7, 1935, Serial No. 55,288

Term of patent 7 years

To all whom it may concern:

Be it known that I, Arthur C. Ansley, a citizen of the United States, residing at 156 West 20 Street, New York, in the county of New York and State of New York, have invented a new, original, and ornamental Design for Phonograph Pick-ups, of which the following is a specification, reference being had to the accompanying drawing, forming part thereof.

The figure is a perspective view of a phonograph pick-up, showing my new design.

I claim:

The ornamental design for a phonograph pick-up, as shown.

ARTHUR C. ANSLEY.
